U.S. Cl. D23—96

FIG. 1 is a perspective view of a combined fireplace heater and grate showing my new design;

FIG. 2 is an end elevational view taken from the left of FIG. 1;

FIG. 3 is a top plan view of FIG. 1;

FIG. 4 is a front elevational view of FIG. 1;

FIG. 5 is a perspective view of a second embodiment of the design of FIG. 1, the only difference residing in the andirons' appearance;

FIG. 6 is an end elevational view taken from the left of FIG. 5;

FIG. 7 is a top plan view of FIG. 5; and

FIG. 8 is a front elevational view of FIG. 5.

I claim:

The ornamental design for a combined fireplace heater and grate, substantially as shown and described.
